UNITED STATES PATENT OFFICE

147,596

DESIGN FOR A CARD TABLE TRAY

Paul J. Ognibene, Philadelphia, Pa.

Application April 16, 1946, Serial No. 128,660

Term of patent 14 years

(CL. D85—2)

To all whom it may concern:

Be it known that I, Paul J. Ognibene, a citizen of the United States, residing at Philadelphia, in the county of Philadelphia and Commonwealth of Pennsylvania, have invented a new, original, and ornamental Design for a Card Table Tray, of which the following is a specification, reference being had to the accompanying drawing, constituting a part thereof.

Fig. 1 is a top perspective view of a card table tray showing my new design, and

Fig. 2 is a bottom perspective view thereof.

I claim:

The ornamental design for a card table tray, substantially as shown.

PAUL J. OGNIBENE.
